UNITED STATES PATENT OFFICE.

PIERRE PAUL GUILLAUME, FILS AÎNÉ, OF PARIS, FRANCE.

DRESS-SHIELD.

SPECIFICATION forming part of Letters Patent No. 427,985, dated May 13, 1890.

Application filed January 4, 1889, Serial No. 295,463. (No model.) Patented in France November 21, 1888, No. 194,247, and in England November 30, 1888, No. 17,442.

To all whom it may concern:

Be it known that I, PIERRE PAUL GUILLAUME, Fils Aîné, a citizen of France, residing in Paris, in the French Republic, have invented a new and useful Improvement in Dress-Preservers, (for which I have obtained patents in England, No. 17,442, dated November 30, 1888, and France November 21, 1888, No. 194,247,) of which the following is a specification.

The object of this invention is to obviate fixing the dress-preserved in the dress by passing the needle through the water-proof material constituting the inside portion of the dress-preserved, as the needle is thereby frequently broken, in addition to which the material becomes puckered and at the same time the punctures therein lessen the efficacy of the dress-preserved as a protector from perspiration. I therefore provide the preserver with a binding and a part or parts of some soft substance—such as silk, cotton, or some equivalent material—running all round the outer and free edges, and through these parts the sewing to the dress is effected in fixing the article in the position desired. This same band of soft substance can serve to secure the water-proof material in its place inside the outer covering of cloth. Dress-preservers so constructed can be readily fixed or removed and placed in other garments when or if required.

Figure 1 of the accompanying drawings is a front view of a dress-preserved embodying my invention. Fig. 2 is a transverse section taken at the line 1 2 of Fig. 1. Figs. 3 and 4 are similar views of a modified construction, Fig. 4 being a section on line 3 4 of Fig. 3. Fig. 5 is a side view of another modification.

The same letters of reference indicate like parts in the respective figures.

a is the outer face of the dress-preserved, *b* being a thin sheet of impermeable material—

such as gutta-percha, india-rubber, oil-silk, or such like substance—forming the inside. Both 45 these are independent, and are simply united by sewing a binding *c* round the edges. When the dress-preserved is so completed, I attach to this binding *c* a border *d* of some soft substance—such as silk, cotton, or some equivalent material. This border may be connected to the dress-preserved in any other convenient manner, so long as it is left free for attaching it to the dress or other garment, so that the stitching is effected through this free 55 border of soft material, thus obviating the necessity of passing the needle through the water-proof substance, which would thereby become puckered and punctured, so that the dress-preserved would lose its efficacy as a protection against perspiration. The braid of the border may also be used for fixing the dress-preserved, which braid would then be, as shown by Figs. 3 and 4, composed of the two parts *c'* and *d'*, united together at *f* by the weaving 65 and afterward continued to form the border *g* of less or greater width. The parts *c'* and *d'* inclose the edges of the texture *a* and of the water-proof material *b*. Consequently the braid of the border offers every facility for fixing the 70 dress-preserved to the dress, or the border or band *d* may be replaced by tongues fixed here and there round the binding *c*, Fig. 5.

What I claim is—

A dress-shield comprising a sheet *b* of water-proof material, a binding *c* for the edges of the same, and a part or parts having free edges beyond the edges of the shield to enable the latter to be secured to the garment by stitching or otherwise without being perforated, substantially as set forth.

PIERRE PAUL GUILLAUME, FILS AÎNÉ.
